UNITED STATES PATENT OFFICE.

RAY H. MANSON, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

DESK STAND.

Application filed March 12, 1920. Serial No. 365,211.

To all whom it may concern:

Be it known that I, RAY H. MANSON, a citizen of the United States, residing at Rochester, in the county of Monroe and 5 State of New York, have invented certain new and useful Improvements in Desk Stands, of which the following is a full, clear, concise, and exact description.

This invention relates to desk stands, and 10 more particularly to desk stands provided with apparatus necessary for use in automatic telephone systems.

It is the purpose of the present invention to provide a telephone desk stand which is 15 simple in construction and inexpensive to manufacture, and which provides a compact and accessible arrangement for the terminal rack, induction coil and dial impulse sender.

20 The various features of the present invention will appear from the detailed description and claims.

Referring to the drawings, Fig. 1 presents a sectional elevation of a desk stand of the 25 present invention with the transmitter mounting broken away; Fig. 2 represents a plan view of a clamp by which a dial impulse sender is secured to the base of the desk stand; Fig. 3 shows one form of terminal rack; Fig. 4 shows various views of a 30 column socket; Fig. 5 shows two views of a socket nut which co-operates with the column socket of Fig. 4; Fig. 6 shows several views of a bracket; Fig. 7 shows a modified 35 form of terminal rack; and Fig. 8 shows a schematic drawing of the several circuits with the various pieces of apparatus mounted in the base of the desk stand, and Fig. 9 shows these circuits in simplified form.

40 Referring to Fig. 1, 10 designates the base of the desk stand. This base has an opening near one edge to receive the column socket 11, shown in Fig. 4, and an opening 12 through which conductors 13 and 14 of the diagram of Fig. 8 enter the desk stand. This base has an annular raised portion 15, also provided with an opening to receive a 45 rotary impulse sender or transmitter of substantially the same character as that disclosed in the patent to Keith, #1,279,352, patented September 17, 1918. A clamp 16, provided with cam portions 16^a engages lugs on the transmitter and is so arranged that by a clockwise movement it secures the dial 50 impulse sender 17, to the raised portion 15 55 of the desk stand. This means for clamping the impulse sender to the base is fully described in applicant's co-pending application, Serial No. 358,506, filed February 18, 1920. 60

A bracket generally designated 18 and shown in the several views of Fig. 6, functions to support the terminal rack and induction coil within the base, and also serves to fasten the base cover 74 in position. The 65 bracket 18 is provided with a circular opening which is just large enough to receive the threaded portion of the column socket 11, and this opening in the bracket has a notch 19 to receive the key 20 of 70 the column socket. This key also engages a notch in the base as shown in Fig. 1, and it will be seen that the key 20 holds the socket, base and bracket against rotation with respect to each other, and it will 75 be later pointed out how the tubular member 38 of the column is similarly held against movement with respect to the base. 80 The bracket is provided with two pairs of outwardly and downwardly extending arms. The first pair of arms has two substantially parallel portions 21 and 22, provided with threaded openings 23 and 24. These arms are of such material that their end portions are slightly resilient so as to allow of spring 85 action in holding the base cover 74 tightly within the base 10 when the base cover retaining screws 76 are in place. The second pair of arms are provided with threaded openings 25 to receive screws 34 inserted 90 through the frame of the induction coil 33. These arms come from under the clamping nut 26, Fig. 1, separately from the first pair of arms so any springing action of the former will not be transmitted to the latter and 95 the induction coil 33 will not be disturbed. The frame of the induction coil is provided with three socket terminals 35 for a purpose to be described. A terminal rack 28 of Fig. 3 provided with terminal connections 100 30, 31 and 32 is secured to the bracket 18 by screws 29 in openings 23. A base cover 74 has an upwardly extending flange to which a strip of leather or other soft material is fastened, and is provided with two apertured embossed portions 75 to receive screws 76 which engage the opening 24 in the bracket. 105

The column of the desk stand comprises a support 37 surrounded by a tubular spacing member 38. The support 37 has its ends up-turned and provided with openings. 5 The upper end of the support 37 is fastened to a mounting 81 for the transmitter (not shown) by means of screws 80. This transmitter mounting 81 is provided with an embossed portion of sufficient diameter to receive the tubular member 38. The opening in the lower end of the support 37 is threaded so that the screw 39 inserted through the opening 72 of the column socket can clamp the support and tubular member 38 to the 10 socket. A split wire ring 40 is placed around the bolt 39 to prevent the bolt from dropping out of the socket when the bolt is un-screwed from the support 37. At the 15 upper portion of the support 37 there is pivotally mounted a well known form of switch hook 41 to which a rod 43 is secured. This rod moves in a vertical block of insulation 78, carried by the support 37, and is surrounded by a spiral spring 43, which 20 tends to move the switch hook with its rod 42 upward when the receiver is removed from its switch hook. A switch hook spring 44 is secured to the block of insulation 78 by means of screws 48 and is movable side- 25 wise under the control of the roller 47 carried by rod 42 in its vertical reciprocating movement. At the extreme lower portion of the support, there is secured a second block of insulation in an opening of which 30 there is secured a rod 45 terminating at its upper end in a contact engaged by spring 44, and its lower end extends through the insulation bushed opening 46 of the column socket to engage the spring 32 of the terminal rack. It will thus be seen that when 35 the receiver is removed from the switch hook, the spring 43 forces the rod 42 and its roller 47 upward, permitting the spring 44 to engage the contact of rod 45. 40 In Fig. 7 there is shown a modified form of terminal rack generally designated 82. This rack is of the same length as that shown in Fig. 3, and is also provided with openings by which it is screwed to the horizontal portions 21 of the bracket arms. This 45 rack is provided with terminal connections 84, 85 and 86, and with a cut-out portion 83 to permit adjustment of the screw 39. In this modification it will be noted that 50 spring 32 has been omitted, and it will therefore be necessary that a flexible conductor connects the rod 45 with the terminal 86. 55 In assembling this desk stand the column socket is inserted into the opening of the base 10, so that the key 20 of the socket engages the notch in the base. The bracket 60 19. The socket nut 26 is then secured onto 65

the column socket to clamp the column socket, bracket and base together. The support 37 is inserted into the tubular member 38 with the switch hook 41 resting in the notch in the upper portion of the tubular member 38. The column when thus assembled is inserted into the column socket with the notch in the lower portion of the tubular member 38 engaging the key 20. The screw 39 is now inserted through the opening 72 of the column socket to clamp the column to the base. The terminal rack or block and induction coil are then secured to the bracket 18 by means of screws 29 and 34. The dial impulse sender 17 is placed on the raised portion 15 of the base with the lugs thereof extending through the opening of the base. The clamping ring 16 is then inserted in the lower side of the base and given a clockwise movement by means of the handles 48 so that the cam surfaces engage the lugs of the dial impulse sender to securely clamp it to the base. The various conductors can then be affixed to the binding posts and the cover plate 74 secured to the bracket 18 by means of screws 76. It will be noted that the resilience of the bracket arms cause the base cover to be held securely in position and prevents the holding screws 76 from working loose in service.

When this desk stand is in service, an inspection of the mechanism contained in the upright tube 38, can be readily done by simply loosening screw 39, a sufficient amount to release inner support 37, and disconnecting cord terminal connections from the terminals in the base 10, after which the upright portions 37 and 38 can be entirely removed.

Referring to Fig. 8, there is shown the desk stand with the apparatus of the base in substantially the same position as shown in Fig. 1. The conductors 13 and 14 comprising the desk stand cord are provided at their ends with pin terminals to engage the pin sockets 30. One pin socket is conductively connected with the screw 50 and by means of a spade terminal. Connection is then made through conductor 51 to the impulse springs 52 of the dial impulse sender. The other conductor 13 by means of its pin terminal and socket terminal 30 which is connected to the spring 32, connects with rod 45, and when the roller 47 controlled by the switch hook is elevated, contact is made between the rod 45 and the spring 44 which is connected to the transmitter 53. The conductor 54 connects the transmitter with the primary winding 55 of the induction coil 33, and by means of the spade terminal connected with the screws 31 of the terminal rack, conductor 56 is connected with conductor 57 which in turn leads to the impulse springs 52.

It will be noted that the impulse sender is provided with shunt springs 58. These springs as is well known are controlled by a bushing 59 which permits them to engage each other when the dial sender is in an off-normal position, that is, when it is transmitting impulses. The springs 58, when closed, complete a shunt circuit around the transmitter from the impulse springs 52 to 10 springs 58, conductor 60, and by means of the spade terminal engaged by the screw 31 and the socket terminal 30, its conductor 60 is connected to conductor 61, and conductor 61 in turn is connected to spring 44 leading 15 to the other side of the impulse springs. The receiver 62 is connected to the secondary winding 63 of the induction coil 33, through the socket terminals 35.

It will thus be seen that a desk stand with 20 an offset column and with a simple arrangement of the supporting means for the terminal rack, induction coil and dial impulse sender and in which all parts are readily accessible has been provided.

25 What I claim is:—

1. A desk stand having in combination, a base, a column, said base and column each being provided with an opening, a column socket for connecting said column to said 30 base, a projection on said socket to engage the opening in said column and base, a bracket also provided with an opening to receive said projection, a nut for securing said bracket to said base, and a cover for said 35 base secured to said bracket.

2. A desk stand having in combination, a base with eccentric openings therein, an impulse transmitter secured in one of said 40 openings, a column secured in said second opening, a bracket mounted adjacent said last mentioned opening, said bracket being provided with a plurality of sets of arms, telephonic apparatus mounted on one of said sets of arms, a base cover mounted on said 45 second set of arms, and means to prevent rotation of said bracket with respect to said base.

3. A desk stand having in combination, a base with an eccentric opening therein, a 50 column mounted in said opening, a hook switch mounted on said column, a conducting rod extending from said hook switch through said opening, a bracket mounted adjacent said opening, said bracket being provided with a plurality of sets of arms, a 55 terminal rack mounted on one of said sets of arms, a contact on said terminal rack to resiliently engage said rod, a base cover mounted on the same set of arms, and telephonic apparatus mounted on said second 60 set of arms.

4. In combination, a desk stand base having 65 an eccentric opening therein, a threaded column socket extending into said opening, a column extending into and secured to said

socket, a bracket provided with means to engage said socket, and a nut for holding said socket, base and bracket together, a hook switch mounted in said column, said switch being provided with a rigid member extending through said socket into said base, a terminal rack, said terminal rack being provided with a spring to resiliently engage said member, and a base cover mounted on said bracket. 70

5. In combination, a desk stand base having an eccentric opening therein, a threaded column socket extending into said opening, a column extending into and secured to said socket, a bracket provided with means to engage said socket, a nut for holding said socket, base and bracket together, a hook switch mounted in said column, said switch being provided with a rigid member extending through said socket into said base, means 80 mounted on said bracket to engage said rigid member, and means for preventing rotation of said column, bracket and base with respect to each other. 85

6. In combination, a desk stand base, a column mounted eccentrically on said base, a bracket provided with arms mounted adjacent and extending in a direction to one side of said column, a coil mounted on certain of said arms, and a base cover secured to 90 others of said arms. 95

7. In combination, a desk stand base, a column mounted eccentrically on said base, a bracket provided with arms secured adjacent said column, said arms extending in a direction to one side of said column, a coil mounted on certain of said arms, and a terminal rack and base cover mounted on others of said arms. 100

8. A desk stand having in combination a base with large and small eccentric openings therein, a column secured to said base adjacent said small opening, a bracket provided with arcuate arms mounted adjacent said small opening with its arcuate arms adjacent said large opening, an induction coil suspended from said arcuate arms, a terminal block secured to said bracket adjacent said small opening, and a cover for said base. 105

9. In combination, a desk stand base, a bracket provided with arcuate arms fitted within said base, an induction coil mounted on said arcuate arms; a terminal block also mounted on said bracket, a transmitter mounting, a hollow spacing member engaging at one end said base and at its other end said transmitter mounting, a portion of said mounting extending within said spacing member, a support extending through said spacing member and fastened at one end to said mounting, means for securing said base and said bracket to the other end of said support eccentrically of said base and a cover for said base. 115

10. A desk stand having in combination 130

41
a base, a bracket provided with arcuate arms fitted within said base, an induction coil mounted on said arcuate arms, a terminal block also mounted on said bracket, a transmitter mounting, a hollow spacing member engaging at one end said base and at its other end said transmitter mounting, a support extending through said spacing member and having its ends bent at substantially 5 right angles to the main portion thereof, one of said angular bent portions being connected to said mounting, means for securing said base and said bracket to the other angular bent portion of said support eccentrically of 10 said base, and a cover for said base.

11. A desk stand having in combination a base with an opening therein, a bracket for telephonic apparatus fitted within said base, said bracket being provided with arcuate 20 arms and with an opening, an induction coil suspended from said bracket, a transmitter mounting, a tabular spacing member separating said mounting from said base, a support extending through said spacing member 25 and having one end secured to said mounting, and an element passing through the opening in said bracket and said base for securing the other end of said support to said base.

12. A desk stand having in combination, a base provided with an opening therein, a bracket for telephonic apparatus fitted within said base, said bracket having an opening therein, an induction coil suspended from said bracket, a transmitter mounting, supporting means for said mounting including a threaded portion extending through the opening in said base and bracket, and a nut engaging said threaded portion to secure said base and bracket to said threaded portion.

13. In a telephone desk stand, a hollow base having an opening therein, a bracket secured to said base, said bracket being provided with an opening and also being provided with a pair of diverging arms, an induction coil mounted on said diverging arms, a transmitter mounting, a support having its ends bent at substantially right angles to the main portion thereof, one of said angular portions being connected to said transmitter mounting, means extending through the openings in said base and said bracket for connecting said base to said support and a removable cover for said base.

14. In a telephone desk stand, a hollow base having an opening therein, a bracket secured to said base, said bracket having an opening therein and being provided with a pair of diverging arms and a substantially flat portion, an induction coil mounted on 50 said diverging arms, a contact terminal se-

cured to the flat portion of said bracket, a transmitter mounting, a support having its ends bent at substantially right angles to the main portion thereof, one of said ends being connected to said mounting, means extending through the openings in said base and said bracket for securing the same to the other end of said support a removable cover for said base and a hollow tube extending from said transmitter mounting to said base to enclose said support.

15. In combination, a desk stand base having a large eccentric opening, a column mounted eccentrically on said base adjacent to said opening, a bracket provided with arms mounted adjacent said column, said bracket arms extending from said column and bordering said opening, a coil depending from said arms and a cover for said base.

16. In a telephone desk stand, a hollow base, a supporting member extending upwardly from said base, an induction coil within said base, an arcuate bracket for supporting said induction coil in a suspended position, said bracket being provided with a lateral extension, a terminal block mounted on said extension, a bolt extending through said bracket, said bolt being provided with a threaded end portion extending through the upper portion of said base and through the lower end of said supporting member.

17. In a telephone desk stand, a hollow base having a large eccentric opening therein, a supporting member extending upwardly from said base, an induction coil within said base, an arcuate bracket for supporting said induction coil in a suspended position, said bracket being provided with a lateral extension, a terminal block mounted on said extension, a bolt extending through said bracket, said bolt being provided with a threaded end portion extending through the upper portion of said base and through the lower end of said supporting member.

18. In a telephone desk stand, a hollow base, a supporting member extending upwardly from said base, a bracket having a substantially flat portion and a pair of diverging arms lying in a plane intersecting the plane of said flat portion, an induction coil suspended from said pair of arms, a terminal block mounted on said bracket, and a bolt extending through the flat portion of said bracket, said bolt being provided with a threaded end portion extending through the upper portion of said base and through the lower end of said supporting member.

In witness whereof, I hereunto subscribe my name this 10th day of March A. D. 1920.

RAY H. MANSON.
